CLAIM

The ornamental design for a headgear assembly for breathing interface, as shown and described.

DESCRIPTION

FIG. 1 is a front, left side, top perspective view of a headgear assembly for breathing interface;

FIG. 2 is a rear, right side, top perspective view thereof;

FIG. 3 is a right side view thereof;

FIG. 4 is a rear view thereof;

FIG. 5 is a left side view thereof;

FIG. 6 is a top view thereof;

FIG. 7 is a front view thereof;

FIG. 8 is a bottom view thereof;

FIG. 9 is a rear, right side, top perspective view of a crown strap portion of the headgear assembly for breathing interface;

FIG. 10 is a top view thereof;

FIG. 11 is a rear view thereof;

FIG. 12 is a left side view thereof;

FIG. 13 is a top view thereof;

FIG. 14 is a front view thereof; and,

FIG. 15 is a bottom view thereof.

Broken lines are used to illustrate portions of the headgear assembly for breathing interface that form no part of the claimed design.

1 Claim, 15 Drawing Sheets
